UNITED STATES PATENT OFFICE.

HUGO H. SCHNEIDER, OF SEATTLE, WASHINGTON.

TELEPHONE-RECEIVER.

1,137,235.

Specification of Letters Patent. Patented Apr. 27, 1915.

Application filed March 13, 1914. Serial No. 824,438.

To all whom it may concern:

Be it known that I, HUGO H. SCHNEIDER, a citizen of the United States, residing at Seattle, in the county of King and State of Washington, have invented certain new and useful Improvements in Telephone-Receiver, of which the following is a specification.

This invention relates in general to telephones of the class which are operated by the aid of an electric current, and more particularly to the diaphragm and its accessories in a telephone receiver.

The object of the invention is to improve telephonic articulation.

To this end my invention consists in the construction and combination of parts forming a telephone receiver hereinafter more fully described, and definitely stated in the claims, reference being had to the accompanying drawings, in which:

Figure 1 represents my invention in telephone receivers in side view, partly broken away, and a diagram of a single phase, alternating current generator. Fig. 2 shows a modification of the same.

Numeral 1 represents the diaphragm of my telephone receiver of any suitable material having a permanent magnet 2 attached to it.

N may be considered the north or positive pole, and S the south or negative pole of this magnet. A core 3 of soft iron—here shown in horseshoe shape—is located with its ends 4 and 5 opposite to the poles N and S, respectively.

The two arms 4 and 5 are wound in any usual manner to form a magnet when vitalized, and for the latter purpose a source 6 of alternating current electricity is connected by wires 7 and 8 with the coils 4 and 5. In operation, when the alternating current comes in, or is positive, at pole 5, the adjacent negative pole S of the diaphragm will thereby be attracted, and at the same time the pole 4 will be negative and will consequently attract the positive pole N of the diaphragm, but the succeeding alternate impulse of the current will reverse the action, making pole 4 positive and pole 5 negative, whereby, the polarity being now the same as the adjacent poles N and S, the diaphragm will be repelled. A stretched string

or diaphragm, if set to vibrating freely, swings to and fro across its normal line or plane of rest. In the primitive telephone comprising two diaphragms with a taut string connecting their centers the diaphragms were so strained that the normal form was a cone, and the constant pull in one direction did not permit vibration beyond the limit of the string. This, I think, is one of the reasons why the articulation of the string telephone was very imperfect, and I think that a similar result is produced, though in a lesser degree, in the class of telephones which use a magnet in connection with the diaphragm, but arrange the magnet to exert only an attracting or pulling influence. Therefore, I employ a magnet endowed with both pulling and pushing force to assist the diaphragm in reproducing both the outward and inward undulations of sound waves. By this means the vibrations of the diaphragm in reproducing articulate sounds will be assisted both to and fro, rendering the quality of the sound reproduced more nearly perfect.

In the modification shown in Fig. 2 a soft iron core 10, provided with the usual windings 11 and 12, is fixed to the diaphragm 9, and is connected by means of wires 14 and 15 with a source 13 of alternating current, and the action of the diaphragm is like that described in Fig. 1. In Fig. 1 the diaphragm carries a magnetic field the direction of which is fixed, and in Fig. 2 the diaphragm carries a magnetic field the direction of which is reversible by the action of the alternating current. It may be found practicable to make the diaphragm 1 in Fig. 1 a permanent magnetic disk and dispense with the attached part 2.

While I have herein shown the simplest means which I have yet devised for producing and arranging a permanent magnetic field to coact with a reversible magnetic field upon a telephone diaphragm, yet I do not confine myself to the specific construction herein shown and described, nor to any specific means for rendering one of the fields permanently magnetic while in service.

I claim:

1. In a telephone receiver, a diaphragm,

a permanent magnet secured thereto; an electro-magnet located with its two poles adjacent to the poles of the permanent magnet; and a source of alternating electric current connected with the electro-magnet.

2. In a telephone receiver, a source of alternating current; a magnet of fixed polarity and a magnet of reversible polarity located adjacent one to the other to coact,

and a diaphragm carrying one of the said 10 magnets.

In testimony whereof I affix my signature in presence of two witnesses.

HUGO H. SCHNEIDER.
